UNITED STATES PATENT OFFICE.

JOSEPH G. HUYE, OF NEW ORLEANS, LOUISIANA.

BOX.

1,249,098.

Specification of Letters Patent.

Patented Dec. 4, 1917.

Application filed June 30, 1917. Serial No. 177,896.

To all whom it may concern:

Be it known that I, JOSEPH G. HUYE, a citizen of the United States, residing at New Orleans, in the parish of Orleans and State of Louisiana, have invented certain new and useful Improvements in Boxes, of which the following is a specification.

This invention relates to collapsible set-up boxes, more particularly to paste-board hat-boxes, candy-boxes and similar receptacles and may be made in any desired form, it being understood of course that the outline of the top and bottom or end portions or sections shall correspond to the cross-sectional form of the body.

The primary object of this invention is to improve the locking means for sectional collapsible set-up boxes consisting of two or more sections, two of which may be easily and securely locked together in accordance herewith.

In the accompanying drawings:

Figure 1 represents a perspective view of a box, of square form, in which my invention is embodied, the upper and lower portions being partially broken away;

Fig. 2, a top plan view of the same, with the cover removed and part of the walls shown in section and the rest broken away, two of the spreading leaves or locking leaves 3 being in locking position and two folded in free position;

Fig. 3, a superposed perspective view of portions of the body and the flange or lip 5 carrying the engaging elements;

Fig. 4, a fragmentary sectional view on the line 4—4 of Fig. 2, the wall of the body being broken away to show the inner face of the lip 5 in elevation;

Fig. 5, a detail superposed perspective view of the parts of the box ready to be packed for shipment, the top and bottom telescoping and receiving between them the body 8 in folded condition;

Fig. 6, a view, similar to Fig. 1, of an octagonal form of box, the side walls being slightly broken away to show the spreading leaves 3 in spreading or locking position in this form or style of box;

Fig. 7, a view, similar to Fig. 3, of a modified form; and Fig. 8, a fragmentary horizontal longitudinal sectional view through such modified form.

Referring now in detail to the drawings, the box illustrated consists of three parts or sections, the top A having the usual flange or

lip, the body section 8 snugly fitting into this flange or lip with its upper portion and with its lower portion similarly fitting into the correspondingly shaped flange or lip 5 of the bottom 4.

Each face or wall of the lip or flange 5, in the angular shapes, such as shown, is, preferably, provided with at least two angular openings 6 to receive the correspondingly shaped lugs 7 formed by stamping out on three sides the material of body 8 and bending it on its forth connected side back against the adjacent face of body 8 and securing it in such position by any suitable method or means, such as the staple 9. The position of the lugs 7 on the body 8 corresponds to the position of the holes 6 in the lip or flange 5, so that when the body 8 is slightly deformed and has its lower end portion inserted into the lip 5 of end 4 its lugs 7 will enter the corresponding holes 6 in the lip 5 and the edges of the lugs 7 and the walls of the respective holes 6 will engage and prevent any movement of the parts 4, 5 and 8 with relation to each other, except laterally inwardly or outwardly, so long as the body 8 retains its normal shape.

When the parts 8 and 4 have been assembled as above with the lugs 7 projecting into or through the respective openings 6, the spreading or locking leaves 3, formed integral with a sheet of paste-board 1 secured flat against the upper face of the bottom 4 by staples 2 or by any other suitable means or method, are turned down on their scored lines 10 so that their edges engage the adjacent portions of the inner walls of the body 8 and force the same outwardly so that the outer face of the body 8 will be held tightly against the inner wall or walls of lip or flange 5, preventing the escape of lugs 7 from their respective holes 6.

When assembled as above the parts cannot become separate from, or twisted or disarranged with relation to, each other in normal use.

To pack for shipment the parts are separated, the locking leaves preferably folded, as shown by Fig. 5, the body flattened and folded on itself, as shown in said figure, and placed in the bottom 4, which will then be fitted in the top A.

In the modified form illustrated in Figs. 7 and 8, the construction and operation is in all respects the same as above described except that lugs 11 projecting farther from

the face of the body 8 and through their respective holes 6 and formed by stamping out, on three sides in each instance, folding back one over the other, to form an additional thickness, and held in position by staples 9, or any other suitable means, are substituted for the lugs 7, above described.

Any suitable fibrous or metallic material may be used throughout or wherever desired.

10 Having thus described my invention, what I claim as new and desire to secure by Letters Patent is:

1. A receptacle comprising two portions, one of said portions being provided with 15 projections and the other of said portions being formed to snugly receive said projections, in combination with spreading means for holding one of said sections in its normal spread condition.

20 2. A receptacle comprising two sections provided with coöperating perforations and projections, in combination with independent spreading means for holding said parts in normal position to prevent the escape of 25 said projections from said perforations.

3. A receptacle comprising a body section and a cover section having a lip provided with holes, the body section being provided 30 with projections adapted, in assembled position, to project into said holes, in combination with spreading means adapted to hold

one of said sections in its normal spread condition to prevent the escape of such projections from their respective holes.

4. A receptacle having two sections, one of said sections being provided with integral lugs and the other of said sections being provided with holes to receive said lugs, in combination with independent spreading means for holding one of said sections in its 40 normal position to prevent the disengagement of said lugs from the walls of said holes respectively.

5. A receptacle having two sections, one of said sections being provided with lugs 41 and the other being provided with holes to receive said lugs; in combination with means secured to one of said sections to keep the other of said sections in its normal spread condition.

6. A receptacle having two sections, one of said sections being provided with integral lugs and the other being provided with holes to receive said lugs, in combination with means secured to one of said sections 5 and adapted to engage the other section to keep it in proper form, preventing the disengagement of said lugs from the walls of said holes.

In testimony whereof, I have signed my name to this specification.

JOSEPH G. HUYE.
